ELMER R. CORWIN, OF CLYDE, ILLINOIS, ASSIGNOR TO MONARCH TELEPHONE MANUFACTURING COMPANY, OF CHICAGO, ILLINOIS, A CORPORATION OF ILLINOIS.

TELEPHONE SYSTEM.

No. 888,871.

Specification of Letters Patent.

Patented May 26, 1908.

Application filed May 11, 1906. Serial No. 316,359.

To all whom it may concern:

Be it known that I, ELMER R. CORWIN, citizen of the United States, residing at Clyde, in the county of Cook and State of Illinois, have invented a certain new and useful Improvement in Telephone Systems, of which the following is a full, clear, concise, and exact description, reference being had to the accompanying drawings, forming a part 10 of this specification.

My invention relates to telephone exchange practice, and has for its general object the provision of simplified mechanism and circuits for governing the operation of 15 calling and supervisory or disconnect signal devices and calling and supervisory pilot signal devices.

By means of my invention I may, through the agency of a single relay associated with 20 each telephone line, a jack of said line, a plug insertible in said jack, and suitable circuit connections, effect, in coöperation with the sub-station apparatus, complete control of line and supervisory or disconnect signal devices and also of pilot calling and supervisory 25 signal devices.

In practicing my invention, I desirably employ a line relay for each telephone line having two armature switches that are 30 closed upon contacts when the line relay is energized, one of said armature switches serving to close the line signal circuit, while the other armature switch completes one of two gaps in a shunt about the supervisory or disconnect signal device, the other opening in 35 said shunt being established by a plug when it is inserted in the jack of said line. As the line relay is energized during the entire time the subscriber has his telephone off its hook, 40 the shunt about the supervisory or disconnect signal device is maintained intact so that said signal device does not operate or glow, and, in order that a special cut-off relay need not be employed for removing the line 45 signal devices when the operator plugs into the jack, the same shunt or practically the same shunt or a portion of the same shunt that is used for shunting the supervisory signal device is also preferably used for shunting 50 the line signal device. Each line signal device, therefore, is shunted as soon as the operator answers the same. The telephone line just spoken of is understood to be the calling telephone line, but the control of the 55 signal devices associated with the called tele-

phone line is very much the same, it, of course, being understood that in the case of a called telephone line the line signal device of such line is not operated when the called subscriber removes his telephone from its hook, 60 for this operation has been guarded against by the operator in engaging the connecting plug with the jack of the called line. In other words, in the preferred embodiment of the invention, in so far as the control of the 65 signal devices is concerned, the connecting ends of the cord circuits are preferably like the answering ends thereof.

A subscriber, in initiating a connection, operates his line relay (which remains operated while the calling subscriber's receiver is removed from its hook), thereby completing a local circuit at the exchange that includes the line signal device, a portion of which local circuit is common to a plurality 70 of such circuits, which common portion contains a pilot call signaling device, the part of the pilot signaling device included in this common portion of the circuit being desirably a low resistance relay which controls 75 the operation of an armature switch that determines the illumination of a pilot lamp. When the line relay is energized, a special short circuiting switch, operated by the line relay, is closed to close one gap in the shunt 80 about the line signal device, the other gap of which is closed by the inserted plug, as stated hitherto.

As stated hitherto, the supervisory or disconnect signal device has, by this extra line 90 relay armature switch and the plug and jack contacts, established a shunt about the supervisory signal device, it being still remembered that the line relay is energized while the subscriber has his telephone removed from its hook, but when the subscriber restores his receiver to its hook, the armature switch determining the opening at one portion in the shunt is released to open the shunt at this portion, whereby the 95 supervisory or disconnect signal device is included in circuit, a part of which circuit, as is understood, being established by the plug and registering contact of the jack into which the plug has been inserted. The 100 operator, in response to the clearing-out signal, withdraws the plug, and thereby effaces the said signal. It will be also understood that while the shunt about the 105 line signal device has also been opened at 110

one of the line relay switch contacts when a subscriber restores his receiver upon its hook, the other line relay switch contact is also opened, whereby the line signal device is included in open circuit, so that it does not again effect a signal.

Each disconnect or supervisory signal circuit desirably contains a portion which is common to a group of supervisory or disconnect signal circuits, which common portion preferably includes a relay that determines the illumination of a supervisory or disconnect pilot lamp. It will be understood that the shunt is not established about the pilot call signal device until all of the calling subscribers common to said pilot call signal device have had their calls attended to. It will also be understood that the shunt about the supervisory pilot device is not removed until all of the subscribers connected with the cords common to said supervisory pilot device have restored their receivers, and that the pilot signal device is not restored to normal or non-indicating position until all of the plugs of the cords common thereto are withdrawn from the jacks.

My invention finds a large utility in connection with subscribers' telephone lines, but I do not wish to be limited in all embodiments of the invention to telephone lines extending from exchanges to subscribers' stations, as it is obvious that my invention may have other applications.

I will explain my invention more fully by reference to the accompanying drawing and will point out more clearly advantages of my invention in connection therewith, in which—

Figure 1 illustrates the invention as applied to telephonic exchange systems including subscribers' lines. Fig. 2 is a schematic view more briefly outlining the circuits that are shown in Fig. 1.

Like parts are indicated by similar characters of reference in both figures.

There are indicated two of many substations, A, B, each in the embodiment of the invention shown, having a transmitter 1, a receiver 2, a call bell 3, a switch-hook 4, a condenser 5, and an impedance coil 6, together with suitable contacts and circuit connections, whereby, when the telephone receivers 2 are upon their switch-hooks, the bells 3, together with the condensers 5, are bridged across the sides of the telephone lines 7, 8, and whereby when the telephone receivers are removed from their hooks, the bridges including said signaling bells are opened and the transmitters are thrown into conductive connection with the lines, whereby battery may be fed thereto through the impedance coil 6, and whereby these currents may be impressed upon the lines at the substations at the transmitters or may be re-

ceived at the receivers. I do not wish to be limited to the precise sub-station circuits indicated.

The limbs 7, 8 of the telephone lines are, in multiple switch-board practice, multiplied to sleeve contacts or thimbles 9 and tip springs or contacts 10, respectively, of multiple spring jacks, though the invention may be useful in connection with switch-boards that are not multiple switch-boards, in which case but one spring jack need be supplied to a line. In multiple switch-board practice, one of the jacks may act as an answering jack, the answering jacks, as is understood, being suitably distributed among the different sections of the switch-board, the multiple jacks being multiplied to the several sections of the switch-board, which grouping arrangement, or any other preferred grouping, is well understood.

In the embodiment of the invention shown, the line relays 11 have their windings desirably permanently associated with the corresponding telephone lines and the common talking battery 12, the circuit of this talking battery desirably having one of its poles permanently connected with one side of the subscriber's circuit through the relay 11, and the other pole connected with the other side of the subscriber's circuit through the impedance device 13. When a subscriber removes his telephone, the line relay 11 becomes energized, whereby a circuit through the line signal device 14 of the calling subscriber may be closed by way of a line relay switch 15 and its front contact, said armature switch 15 being desirably, though not necessarily, connected with one pole of a special signaling battery 16, the other pole of which is connected through the line signal device 14 to the front contact of said switch 15. In the portion of the line signal circuit 17 that is common to a group of line circuits, there is included a pilot signal device. In the form of the invention shown, the winding 18 of a pilot signal device relay is included in this common circuit portion 17, the armature switch of this relay governing the circuit condition of the pilot line lamp 19.

On the initiation of a call, a second armature switch 20 is also operated to engage its front contact, this armature switch and its contact closing one gap in a shunt conductor 21 provided for inclusion about the signal device 14, the remaining gap in which shunt conductor 21 is established by the sleeve of the inserted plug, which connects the sleeve talking contact 9 of the jack containing the plug with an extra contact 22 in connection with the contact of the armature switch 20, the said sleeve of the plug being also a talking contact.

I do not wish to be limited to the stated registering contacts of the plugs and jacks for establishing one closure of the shunt circuit.

It will be seen that as soon as the operator responds to a calling subscriber, the signal occasioned by the device 14 is effaced without the aid of a cut-off relay. In the case of 5 a calling subscriber, the shunt is partially closed at 20 before it is closed at 22; in the case of a called line, the shunt is partially established at 22 before it is established at 20, which latter establishment is occasioned 10 when the called subscriber responds. When the subscribers are through conversation, the shunt is opened at 22, but at the same time the armature switches 15 fall back, so that the signal device 14 is in open circuit.

15 It will be apparent that the calling signal device 14 operated by a calling subscriber cannot again be operated during an established connection, on account of the presence of the plug in the jack corresponding to the 20 call signal device.

When a subscriber restores his telephone upon its switch-hook, his line relay 11 becomes deenergized, whereby the short or shunt circuit 21 is opened at 20, thereby 25 opening the short or shunt circuit about the supervisory or disconnect signal device, there being two such devices 23, 24, where double supervision is desired, and it may be assumed that the device 23 corresponds to the calling 30 subscriber and the device 24 corresponds to the called subscriber, for sake of example.

Current from the battery or source 16 is now at liberty to flow through the lamp 23 (or the lamp 24, or both lamps, as the case 35 may be), thereby furnishing a supervisory or disconnect signal to the operator. If it is a disconnect signal, the operator effaces the same by pulling down the connection between the subscribers.

40 I have indicated a relay 25 in a circuit portion 26 common to a group of lamps 23 which becomes energized, on account of the removal of the shunt 21, when any of the subscribers in connection with the cord circuits 45 having said group of lamps 23 have restored their receivers upon their switch-hooks, whereby the pilot signal lamp 27 becomes energized, the signal occasioned by this device 27 being effaced, when all of the plugs 50 corresponding thereto are removed from the engaging jacks.

In Fig. 1 of the drawing the parts shown upon the right hand having functions similar to parts shown upon the left hand are given 55 similar characters of reference, with the exception of the supervisory signal devices, one of which is peculiar to the calling subscriber and the other of which is peculiar to the called subscriber.

60 While I have shown two supervisory signal devices, I do not wish to be limited to this number of disconnect signal devices in the cord circuits.

I have not indicated the operator's listening and ringing keys and associate appara-

tus, as these instrumentalities and the functions thereof are well understood by those skilled in the art, and their application to the system shown is very apparent.

While I have illustrated a multiple switch- 70 board system and have shown and specifically described lamps for effecting display of signals, I do not wish to be limited to such character of switch-boards, nor to the use of the lamps for said purposes.

The shunt circuits about the line and supervisory signal devices and the corresponding pilot signal devices are desirably of so low resistance as to constitute short circuits about said devices, though I do not wish to 80 be limited to shunt circuits that have so little resistance as to constitute short circuits, as I consider it to be within the scope of my invention to employ shunt circuits without regard to the degree of resistance contained 85 therein, but of such electrical character as to prevent such an operation of the signal devices about which the shunts are placed as it is desired to avoid by said short or shunt circuits, as herein fully set forth.

90 I have herein shown a telephone exchange system in which the cord circuits are each provided with two plugs, and I have shown spring jacks for receiving the answering plugs. It is obvious, however, that characteristics of my invention are applicable for other types of telephone exchange systems, and I do not, therefore, wish to be limited to those systems in which link circuits having 95 two manually operated plugs are employed.

100 While I have shown spring jacks for the telephone lines, I do not wish to be limited in all embodiments of the invention to such types of connecting switches.

105 It is obvious that changes may be made from the embodiment of the invention herein particularly shown and described without departing from the spirit of my invention, and I do not, therefore, wish to be limited to the precise construction and arrangement herein shown, but,

Having thus described my invention, I claim as new and desire to secure by Letters-Patent:—

115 1. In a telephone exchange system, the combination with telephone lines, of jacks therefor, cord circuits for connection with the jacks, disconnect signal circuits corresponding to the cord circuits, said disconnect signal circuits having a common portion, a 120 pilot signal device included in said common portion, and means in association with the telephone lines extraneous to the cord circuits acting in combination with the plugs and jacks to govern the operation of said pilot signal device.

125 2. In a telephone exchange system, the combination with telephone lines, of jacks therefor, cord circuits for connection with the jacks, disconnect signal circuits corre-

sponding to the cord circuits, said disconnect signal circuits having a common portion, a pilot signal device included in said common portion, and line relays in association with the telephone lines acting in combination with the plugs and jacks to govern the operation of the pilot signal device.

3. In a telephone exchange system, the combination with telephone lines, of jacks therefor, cord circuits for connection with the jacks, disconnect signal circuits corresponding to the cord circuits, each signal circuit including a portion of a talking conductor of a corresponding cord circuit, said disconnect signal circuits having a common portion, a pilot signal device included in said common portion, and means in association with the telephone lines extraneous to the cord circuits acting in combination with the plugs and jacks to govern the operation of said pilot signal device.

4. In a telephone exchange system, the combination with telephone lines, of jacks therefor, cord circuits for connection with the jacks, disconnect signal circuits corresponding to the cord circuits, each signal circuit including a portion of a talking conductor of a corresponding cord circuit, said disconnect signal circuits having a common portion, a pilot signal device included in said common portion, and line relays in association with the telephone lines acting in combination with the plugs and jacks to govern the operation of the pilot signal device.

35 5. In a telephone exchange system, the combination with telephone lines, of jacks therefor, cord circuits for connection with the jacks, disconnect signal circuits corresponding to the cord circuits, each signal circuit including or adapted to have included as a part thereof a talking conductor of a jack and an engaging contact of a plug, said disconnect signal circuits having a common portion, a pilot signal device included in said common portion, and means in association with the telephone lines extraneous to the cord circuits acting in combination with the plugs and jacks to govern the operation of said pilot signal device.

50 6. In a telephone exchange system, the combination with telephone lines, of jacks therefor, cord circuits for connection with the jacks, disconnect signal circuits corresponding to the cord circuits, each signal circuit including or adapted to have included as a part thereof a talking conductor of a jack and an engaging contact of a plug, said disconnect signal circuits having a common portion, a pilot signal device included in said common portion, and line relays in association with the telephone lines acting in combination with the plugs and jacks to govern the operation of the pilot signal device.

65 7. In a telephone exchange system, the combination with telephone lines, of jacks

therefor, cord circuits for connection with the jacks, a pilot line signal device common to said telephone lines, and shunt conductors in connection with said pilot line signal device for effacing the signals it occasions, 70 which shunt conductors include registering contacts of plugs of the cord circuits and engaging jacks.

8. In a telephone exchange system, the combination with telephone lines, of jacks 75 therefor, cord circuits for connection with the jacks, line signal devices for said telephone lines, shunt conductors in connection with said line signal devices for effacing the signals they occasion, which shunt conductors include registering contacts of plugs of the cord circuits and engaging jacks, and line relays for the telephone lines, said relays having armature switches serving, when operated, to establish the corresponding line 80 signal circuits and to constitute and establish other connections in said shunt conductors.

9. In a telephone exchange system, the combination with telephone lines, of jacks 90 therefor, cord circuits for connection with the jacks, a pilot line signal device common to said telephone lines, shunt conductors in connection with said pilot line signal device for effacing the signals it occasions, which 95 shunt conductors include registering contacts of plugs of the cord circuits and engaging jacks, and line relays for the telephone lines, said relays having armature switches serving, when operated, to establish the corresponding line signal circuits and to constitute and establish other connections in said 100 shunt conductors.

10. In a telephone exchange system, the combination with telephone lines, of jacks 105 therefor, cord circuits for connection with the jacks, line signal devices for said telephone lines, shunt conductors in connection with said line signal devices for effacing the signals they occasion, which shunt conductors include registering contacts of plugs of the cord circuits and engaging jacks, line relays for the telephone lines, said relays having armature switches serving, when operated, to establish the corresponding line 110 signal circuit and to constitute and establish other connections in said shunt conductors, and supervisory or disconnect signaling circuits established by plugs and engaging contacts of jacks, the signal device of each of 115 which latter circuits being shunted by the switching mechanism of the corresponding line relay when said mechanism is operated.

11. In a telephone exchange system, the combination with telephone lines, of jacks 125 therefor, cord circuits for connection with the jacks, a pilot line signal device common to said telephone lines, shunt conductors in connection with said pilot line signal device for effacing the signals it occasions which 130

- shunt conductors include registering contacts of plugs of the cord circuits and engaging jacks, line relays for the telephone lines, said relays having armature switches serving, when operated, to establish the corresponding line signal circuit and to constitute and establish other connections in said shunt conductors, and supervisory or disconnect signaling circuits established by plugs and engaging, when operated, to establish the corresponding line signal circuit and to constitute and establish other connections in said shunt conductors, and supervisory or disconnect signaling circuits established by plugs and 50
- 10 engaging contacts of jacks, the signal device of each of which latter circuits being shunted by the switching mechanism of the corresponding line relay when said mechanism is operated.
- 15 12. In a telephone exchange system, the combination with telephone lines, of jacks therefor, cord circuits for connection with the jacks, line signal devices for said telephone lines, conducting media in connection with said line signal devices for effacing the signals they occasion, which media include registering contacts of plugs of the cord circuits and engaging jacks, line relays for the telephone lines, each relay having armature 55
- 20 switching mechanism which serves, when operated, to establish the corresponding line signal circuit and to constitute and establish another connection in said conducting media, supervisory or disconnect signaling circuits established by plugs and engaging contacts of jacks, and a pilot signal device including a conducting portion common to said latter signaling circuits and shunted by the actuated switching mechanism of the lines relays.
- 25 13. In a telephone exchange system, the combination with telephone lines, of jacks therefor, cord circuits for connection with the jacks, line signal devices for said telephone lines, shunt conductors in connection with said line signal devices for effacing the signals they occasion, which shunt conductors include registering contacts of plugs of the cord circuits and engaging jacks, line relays for the telephone lines, said relays having armature switches serving, when operated, to establish the corresponding line signal circuit and to constitute and establish other connections in said shunt conductors, supervisory or disconnect signaling circuits established by plugs and engaging contacts of jacks, and a pilot signal device including a conducting portion common to 60
- 30 said latter signaling circuits and shunted by the actuated switching mechanism of the line relays.
- 35 14. In a telephone exchange system, the combination with telephone lines, of jacks therefor, cord circuits for connection with the jacks, a pilot line signal device common to said telephone lines, conducting media in connection with said line signal devices for effacing the signals they occasion, which media include registering contacts of plugs of the cord circuits and engaging jacks, line relays for the telephone lines, said relays having armature switches serving, when operated, to establish the corresponding line signal circuit and to constitute and establish another connection in said conducting media, supervisory or disconnect signaling circuits established by plugs and engaging contacts of jacks, the signal device of each of which latter circuits being shunted by the switching mechanism of the corresponding line relay when said mechanism is operated, and a pilot signal device included in a conductor portion common to 65
- 35 15. In a telephone exchange system, the combination with telephone lines, of jacks therefor, cord circuits for connection with the jacks, line signal devices for said telephone lines, shunt conductors in connection with said line signal devices for effacing the signals they occasion, which shunt conductors include registering contacts of plugs of the cord circuits and engaging jacks, line relays for the telephone lines, each relay having armature switching mechanism which serves, 70
- 40 when operated, to establish the corresponding pilot signal circuit and to constitute and establish another connection in said conducting media, supervisory or disconnect signaling circuits established by plugs and engaging contacts of jacks, and a pilot signal device including a conducting portion common to said latter signaling circuits and shunted by the actuated switching mechanisms of the line relays.
- 45 16. In a telephone exchange system, the combination with telephone lines, of jacks therefor, cord circuits for connection with the jacks, line signal devices for said telephone lines, conducting media in connection with said line signal devices for effacing the signals they occasion, which media include registering contacts of plugs of the cord circuits and engaging jacks, line relays for the telephone lines, each relay having armature switching mechanism which serves, when operated, to establish the corresponding line signal circuit and to constitute and establish another connection in said conducting media, supervisory or disconnect signaling circuits established by plugs and engaging contacts of jacks, the signal device of each of which latter circuits being shunted by the switching mechanism of the corresponding line relay when said mechanism is operated, and a pilot signal device included in a conductor portion common to 75
- 50 17. In a telephone exchange system, the combination with telephone lines, of jacks therefor, cord circuits for connection with the jacks, line signal devices for said telephone lines, shunt conductors in connection with said line signal devices for effacing the signals they occasion, which shunt conductors include registering contacts of plugs of the cord circuits and engaging jacks, line relays for the telephone lines, said relays having armature switches serving, when 80

operated, to establish the corresponding line signal circuit and to constitute and establish other connections in said shunt conductors, supervisory or disconnect signaling circuits established by plugs and engaging contacts of jacks, the signal device of each of which latter circuits being shunted by the switching mechanism of the corresponding line relay when said mechanism is operated, and a pilot signal device included in a conductor portion common to said disconnect signal circuits.

18. In a telephone exchange system, the combination with telephone lines, of jacks therefor, cord circuits for connection with the jacks, a pilot line signal device common to said telephone lines, conducting media in connection with said pilot line signal device for effacing the signals it occasions, which media include registering contacts of plugs of the cord circuits and engaging jacks, line relays for the telephone lines, each relay having armature switching mechanism which serves, when operated, to establish the corresponding pilot signal circuit and to constitute and establish another connection in said conducting media, supervisory or disconnect signaling circuits established by plugs and engaging contacts of jacks, the signal device of each of which latter circuits being shunted by the switching mechanism of the corresponding line relay when said mechanism is operated, and a pilot signal device included in a conductor portion common to said disconnect signal circuits.

19. In a telephone exchange system, the combination with telephone lines, of jacks therefor, cord circuits for connection with the jacks, a pilot line signal device common to said telephone lines, shunt conductors in connection with said pilot line signal device for effacing the signals it occasions, which shunt conductors include registering contacts of plugs of the cord circuits and engaging jacks, line relays for the telephone lines, said relays having armature switches serving, when operated, to establish the corresponding line signal circuit and to constitute and establish other connections in said shunt conductors, supervisory or disconnect signaling circuits established by plugs and engaging contacts of jacks, the signal device of each of which latter circuits being shunted by the switching mechanism of the corresponding line relay when said mechanism is operated, and a pilot signal device included in a conductor portion common to said disconnect signal circuits.

20. In a telephone exchange system, the combination with telephone lines, of jacks therefor, cord circuits for connection with the jacks, disconnect signal circuits corresponding to the cord circuits, said disconnect signal circuits having a common portion, a pilot signal device included in said common portion,

and means in association with the telephone lines extraneous to the cord circuits acting in combination with the plugs and jacks to govern the operation of said pilot signal device, said disconnect signal circuits including talking contacts of engaged plugs and jacks.

21. In a telephone exchange system, the combination with telephone lines, of jacks therefor, cord circuits for connection with the jacks, disconnect signal circuits corresponding to the cord circuits, said disconnect signal circuits having a common portion, a pilot signal device included in said common portion, and line relays in association with the telephone lines acting in combination with the plugs and jacks to govern the operation of the pilot signal device, said disconnect signal circuits including talking contacts of engaged plugs and jacks.

22. In a telephone exchange system, the combination with telephone lines, of jacks therefor, cord circuits for connection with the jacks, disconnect signal circuits corresponding to the cord circuits, each signal circuit including a portion of a talking conductor of a corresponding cord circuit, said disconnect signal circuits having a common portion, a pilot signal device included in said common portion, and means in association with the telephone lines extraneous to the cord circuits acting in combination with the plugs and jacks to govern the operation of said pilot signal device, said disconnect signal circuits including talking contacts of engaged plugs and jacks.

23. In a telephone exchange system, the combination with telephone lines, of jacks therefor, cord circuits for connection with the jacks, disconnect signal circuits corresponding to the cord circuits, each signal circuit including a portion of a talking conductor of a corresponding cord circuit, said disconnect signal circuits having a common portion, a pilot signal device included in said common portion, and line relays in association with the telephone lines acting in combination with the plugs and jacks to govern the operation of the pilot signal device, said disconnect signal circuits including talking contacts of engaged plugs and jacks.

24. In a telephone exchange system, the combination with telephone lines, of jacks therefor, cord circuits for connection with the jacks, disconnect signal circuits corresponding to the cord circuits, each signal circuit including or adapted to have included as a part thereof a talking conductor of a jack and an engaging contact of a plug, said disconnect signal circuits having a common portion, a pilot signal device included in said common portion, and means in association with the telephone lines extraneous to the cord circuits acting in combination with the plugs and jacks to govern the operation of said pilot signal device, said disconnect sig-

nal circuits including talking contacts of engaged plugs and jacks.

25. In a telephone exchange system, the combination with telephone lines, of jacks therefor, cord circuits for connection with the jacks, disconnect signal circuits corresponding to the cord circuits, each signal circuit including or adapted to have included as a part thereof a talking conductor of a jack and an engaging contact of a plug, said disconnect signal circuits having a common portion, a pilot signal device included in said common portion, and line relays in association with the telephone lines acting in combination with the plugs and jacks to govern the operation of the pilot signal device, said disconnect signal circuits including talking contacts of engaged plugs and jacks.

26. In a telephone exchange system, the combination with telephone lines, of jacks therefor, cord circuits for connection with the jacks, line signal devices for said telephone lines, shunt conductors in connection with said line signal devices for effacing the signals they occasion, which shunt conductors include registering contacts of plugs of the cord circuits and engaging jacks, line relays for the telephone lines, said relays having armature switches serving, when operated, to establish the corresponding line signal circuit and to constitute and establish other connections in said shunt conductors, and supervisory or disconnect signaling circuits established by plugs and engaging contacts of jacks, the signal device of each of which latter circuits being shunted by the switching mechanism of the corresponding line relay when said mechanism is operated, said disconnect signal circuits including talking contacts of engaged plugs and jacks.

27. In a telephone exchange system, the combination with telephone lines, of jacks therefor, cord circuits for connection with the jacks, a pilot line signal device common to said telephone lines, shunt conductors in connection with said pilot line signal device for effacing the signals it occasions, which shunt conductors include registering contacts of plugs of the cord circuits and engaging jacks, line relays for the telephone lines, said relays having armature switches serving, when operated, to establish the corresponding line signal circuit and to constitute and establish other connections in said shunt conductors, and supervisory or disconnect signaling circuits established by plugs and engaging contacts of jacks, the signal device of each of which latter circuits being shunted by the switching mechanism of the corresponding line relay when said mechanism is operated, said disconnect signal circuits including talking contacts of engaged plugs and jacks.

28. In a telephone exchange system, the combination with telephone lines, of jacks therefor, cord circuits for connection with

the jacks, line signal devices for said telephone lines, conducting media in connection with said line signal devices for effacing the signals they occasion, which media include registering contacts of plugs of the cord circuits and 70 engaging jacks, line relays for the telephone lines, each relay having armature switching mechanism which serves, when operated, to establish the corresponding line signal circuit and to constitute and establish another connection in said conducting media, supervisory or disconnect signaling circuits established by plugs and engaging contacts of jacks, and a pilot signal device including a conducting portion common to said latter 75 signaling circuits and shunted by the actuated switching mechanisms of the line relays, said disconnect signal circuits including talking contacts of engaged plugs and jacks.

29. In a telephone exchange system, the combination with telephone lines, of jacks therefor, cord circuits for connection with the jacks, line signal devices for said telephone lines, shunt conductors in connection with said line signal devices for effacing the 90 signals they occasion, which shunt conductors include registering contacts of plugs of the cord circuits and engaging jacks, line relays for the telephone lines, said relays having armature switches serving, when operated, to establish the corresponding line signal circuit and to constitute and establish other connections in said shunt conductors, supervisory or disconnect signaling circuits established by plugs and engaging contacts of 100 jacks, and a pilot signal device including a conducting portion common to said latter signaling circuits and shunted by the actuated switching mechanism of the line relays, said disconnect signal circuits including talking contacts of engaged plugs and jacks.

30. In a telephone exchange system, the combination with telephone lines, of jacks therefor, cord circuits for connection with the jacks, a pilot line signal device common to 110 said telephone lines, conducting media in connection with said pilot line signal device for effacing the signals it occasions, which media include registering contacts of plugs of the cord circuits and engaging jacks, line 115 relays for the telephone lines, each relay having armature switching mechanism which serves, when operated, to establish the corresponding pilot signal circuit and to constitute and establish another connection in 120 said conducting media, supervisory or disconnect signaling circuits established by plugs and engaging contacts of jacks, and a pilot signal device including a conducting portion common to said latter signaling circuits and shunted by the actuated switching mechanisms of the associated line relays, said disconnect signal circuits including talking contacts of engaged plugs and jacks.

31. In a telephone exchange system, the 130

combination with telephone lines, of jacks therefor, cord circuits for connection with the jacks, a pilot line signal device common to said telephone lines, shunt conductors in connection with said pilot line signal device for effacing the signals it occasions, which shunt conductors include registering contacts of plugs of the cord circuits and engaging jacks, line relays for the telephone lines, said relays having armature switches serving, when operated, to establish the corresponding line signal circuit and to constitute and establish other connections in said shunt conductors, supervisory or disconnect signaling circuits established by plugs and engaging contacts of jacks, and a pilot signal device including a conducting portion common to said latter signaling circuits and shunted by the actuated switching mechanisms of the line relays, said disconnect signal circuits including talking contacts of engaged plugs and jacks.

32. In a telephone exchange system, the combination with telephone lines, of jacks therefor, a cord circuits for connection with the jacks, line signal devices for said telephone lines, conducting media in connection with said line signal devices for effacing the signals they occasion, which media include registering contacts of plugs of the cord circuits and engaging jacks, line relays for the telephone lines, each relay having armature switching mechanism which serves, when operated, to establish the corresponding line signal circuit and to constitute and establish another connection in said conducting media, supervisory or disconnect signaling circuits established by plugs and engaging contacts of jacks, the signal device of each of which latter circuits being shunted by the switching mechanism of the corresponding line relay when said mechanism is operated, and a pilot signal device included in a conductor portion common to said disconnect signal circuits, said disconnect signal circuits including talking contacts of engaged plugs and jacks.

33. In a telephone exchange system, the combination with telephone lines, of jacks therefor, cord circuits for connection with the jacks, line signal devices for said telephone lines, shunt conductors in connection with said line signal devices for effacing the signals they occasion, which shunt conductors include registering contacts of plugs of the cord circuits and engaging jacks, line relays for the telephone lines, said relays having armature switches serving, when operated, to establish the corresponding line signal circuit and to constitute and establish other connections in said shunt conductors, supervisory or disconnect signaling circuits established by plugs and engaging contacts of jacks, the signal device of each of which latter circuits being shunted by the switching mechanism of the corresponding line relay when

said mechanism is operated, and a pilot signal device included in a conductor portion common to said disconnect signal circuits, said disconnect signal circuits including talking contacts of engaged plugs and jacks. 70

34. In a telephone exchange system, the combination with telephone lines, of jacks therefor, cord circuits for connection with the jacks, a pilot line signal device common to said telephone lines, conducting media in connection with said pilot line signal device for effacing the signals it occasions, which media include registering contacts of plugs of the cord circuits and engaging jacks, line relays for the telephone lines, each relay having armature switching mechanism which serves, when operated, to establish the corresponding pilot signal circuit and to constitute and establish another connection in said conducting media, supervisory or disconnect signaling circuits established by plugs and engaging contacts of jacks, the signal device of each of which latter circuits being shunted by the switching mechanism of the corresponding line relay, when said mechanism is operated, and a pilot signal device included in a conductor portion common to said disconnect signal circuits, said disconnect signal circuits including talking contacts of engaged plugs and jacks. 85

35. In a telephone exchange system, the combination with telephone lines, of jacks therefor, cord circuits for connection with the jacks, a pilot line signal device common to said telephone lines, shunt conductors in connection with said pilot line signal device for effacing the signals it occasions, which shunt conductors include registering contacts of plugs of the cord circuits and engaging jacks, line relays for the telephone lines, said relays having armature switches serving, when operated, to establish the corresponding line signal circuit and to constitute and establish other connections in said shunt conductors, supervisory or disconnect signaling circuits established by plugs and engaging contacts of jacks, the signal device of each of which latter circuits being shunted by the switching mechanism of the corresponding line relay when said mechanism is operated, and a pilot signal device included in a conductor portion common to said disconnect signal circuits, said disconnect signal circuits including talking contacts of engaged plugs and jacks. 95

36. In a telephone exchange system, the combination with telephone lines, of jacks or connecting switches therefor, cord circuits for connection with the jacks, line signal devices for said telephone lines, shunt conductors in connection with said line signal devices for effacing the signals they occasion, which shunt conductors include registering talking contacts of plugs or switches of the cord circuits and engaging jacks, and 130

- line relays for the telephone lines, said relays having armature switches serving, when operated, to establish the corresponding line signal circuits and to constitute and establish 5 other connections in said shunt conductors.
37. In a telephone exchange system, the combination with telephone lines, of jacks therefor, cord circuits for connection with the jacks, a pilot line signal device common to 10 said telephone lines, shunt conductors in connection with said pilot line signal device for effacing the signals it occasions, which shunt conductors including registering talking contacts of plugs of the cord circuits and 15 engaging jacks, and line relays for the telephone lines, said relays having armature switches serving, when operated, to establish the corresponding line signal circuits and to constitute and establish other 20 connections in said shunt conductors.
38. In a telephone exchange system, the combination with telephone lines, of jacks therefor, cord circuits, disconnect signal circuits established by plugs and jacks when 25 in engagement, a pilot disconnect signal common to the disconnect signaling circuits, and means associated with said telephone lines for removing the pilot signal from circuit, said disconnect signaling circuits including 30 talking contacts.
39. In a telephone exchange system, the combination with telephone lines, of jacks therefor, cord circuits, disconnect signal circuits established by plugs and jacks when in 35 engagement, a pilot disconnect signal common to the disconnect signaling circuits, and means associated with said telephone lines for shunting the pilot signal from circuit, said disconnect signaling circuits including talking 40 contacts.
40. In a telephone exchange system, the combination with telephone lines, of jacks therefor, cord circuits, disconnect signal circuits established by plugs and jacks when in 45 engagement, a pilot disconnect signal common to the disconnect signaling circuits, and line relays associated with said telephone lines for removing the pilot signal from circuit.
41. In a telephone exchange system, the combination with telephone lines, of jacks therefor, cord circuits, disconnect signal circuits established by plugs and jacks when in 50 engagement, a pilot disconnect signal common to the disconnect signaling circuits, and line relays associated with said telephone lines for shunting the pilot signal from circuit.
42. In a telephone exchange system, the combination with telephone lines, of jacks therefor, cord circuits, disconnect signal circuits established by plugs and jacks when in 55 engagement, a pilot disconnect signal common to the disconnect signaling circuits, and line relays associated with said telephone lines for removing the pilot signal from circuit.
43. In a telephone exchange system, the combination with telephone lines, of jacks therefor, cord circuits, disconnect signal circuits established by plugs and jacks when in 60 engagement, a pilot disconnect signal common to the disconnect signaling circuits, and line relays associated with said telephone lines for shunting the pilot signal from circuit, said disconnect signaling circuits including talking contacts.
44. In a telephone exchange system, the combination with telephone lines, of jacks therefor, cord circuits for connection with the jacks, line signal circuits for said telephone lines, a pilot signal device common to 70 said line signal circuits, line relays, and shunt conductors in connection with said pilot signal device for effacing the signals it occasions, which shunt conductors include registering 75 talking contacts of plugs of the cord circuits and engaging jacks and contacts of line relay switches.
45. In a telephone exchange system, the combination with telephone lines, of jacks therefor, cord circuits for connection with the jacks, line signal circuits for said telephone lines, a pilot signal device common to 80 said line signal circuits, line controlled means, and shunt conductors in connection with said pilot signal device, whose continuity is governed by said line controlled means and the 85 registering contacts of engaged plugs and jacks.
46. In a telephone exchange system, the combination with telephone lines, of jacks therefor, cord circuits for connection with the jacks, line signal circuits for said telephone lines, a pilot signal device common to 90 said line signal circuits, line relays, and shunt conductors in connection with said pilot signal device for effacing the signals it occasions, which shunt conductors include registering 95 talking contacts of plugs of the cord circuits and engaging jacks and contacts of line relay switches.
47. In a telephone exchange system, the combination with telephone lines, of jacks or connecting switches therefor, cord circuits for connection with the jacks, line signal circuits for 100 said telephone lines, a pilot signal device common to said line signal circuits, line controlled means, and shunt conductors in connection with said pilot signal device, whose continuity is governed by said line controlled 105 means and the registering talking contacts of engaged plugs or switches and jacks or switches.
48. In a telephone exchange system, the combination with metallic circuit telephone 110 lines, of jacks or connecting switches therefor, cord circuits having metallic sides for connection with the jacks, line signal devices for 115

said telephone lines, conducting media in connection with said line signal devices for effacing the signals they occasion, which media include registering contacts of plugs or switches of the cord circuits and engaging jacks, line relays for the telephone lines, each relay having armature switching mechanism which serves, when operated, to establish the corresponding line signal circuit and to constitute and establish another connection in said conducting media, and supervisory or disconnect signaling circuits established by plugs and engaging contacts of jacks, the signal device of each of which latter circuits being shunted by the switching mechanism of the corresponding line relay when said mechanism is operated.

49. In a telephone exchange system, the combination with metallic circuit telephone lines, of jacks or connecting switches therefore, cord circuits having metallic sides for connection with the jacks, a pilot line signal device common to said telephone lines, conducting media in connection with said pilot line signal device for effacing the signals it occasions, which media include registering contacts of plugs or switches of the cord circuits and engaging jacks, line relays for the telephone lines, each relay having armature switching mechanism which serves, when operated, to establish the corresponding pilot signal circuit and to constitute and establish another connection in said conducting media, and supervisory or disconnect signaling circuits established by plugs and engaging contacts of jacks, the signal device of each of which latter circuits being shunted by the switching mechanism of the corresponding line relay when said mechanism is operated.

50. In a telephone exchange system, the combination with metallic circuit telephone lines, of jacks or connecting switches therefore, cord circuits having metallic sides for connection with the jacks, line signal devices for said telephone lines, conducting media in connection with said line signal devices for effacing the signals they occasion, which me-

dia include registering contacts of plugs or switches of the cord circuits and engaging jacks, line relays for the telephone lines, each relay having armature switching mechanism which serves, when operated, to establish the corresponding line signal circuit and to constitute and establish another connection in said conducting media, and supervisory or disconnect signaling circuits established by plugs and engaging contacts of jacks, the signal device of each of which latter circuits being shunted by the switching mechanism of the corresponding line relay when said mechanism is operated, said disconnect signal circuits including talking contacts of engaged plugs and jacks.

51. In a telephone exchange system, the combination with metallic circuit telephone lines, of jacks or connecting switches therefore, cord circuits having metallic sides for connection with the jacks, a pilot line signal device common to said telephone lines, conducting media in connection with said pilot line signal device for effacing the signals it occasions, which media include registering contacts or plugs or switches of the cord circuits and engaging jacks, line relays for the telephone lines, each relay having armature switching mechanism which serves, when operated, to establish the corresponding pilot signal circuit and to constitute and establish another connection in said conducting media, and supervisory or disconnect signaling circuits established by plugs and engaging contacts of jacks, the signal device of each of which latter circuits being shunted by the switching mechanism of the corresponding line relay when said mechanism is operated, said disconnect signal circuits including talking contacts of engaged plugs and jacks.

In witness whereof, I hereunto subscribe my name this 30th day of April A. D., 1906.

ELMER R. CORWIN.
